UNITED STATES PATENT OFFICE.

JOHN GWYNNE, OF LONDON, ENGLAND.

DREDGING APPARATUS.

SPECIFICATION forming part of Letters Patent No. 552,285, dated December 31, 1895.

Application filed November 6, 1893. Serial No. 490,154. (No model.) Patented in England December 13, 1892, No. 22,913; in France October 25, 1893, No. 233,629; in Belgium November 29, 1893, No. 107,407; in New South Wales December 29, 1893, No. 4,807; in Italy December 31, 1893, LXIX, 319; in Victoria January 9, 1894, No. 11,074; in Spain February 10, 1894, No. 15,347; in New Zealand February 13, 1894, No. 6,672; in India April 27, 1894, No. 15; in Austria May 19, 1894, No. 166, and in Russia December 31, 1894, No. 24,567.

To all whom it may concern:

Be it known that I, JOHN GWYNNE, a subject of the Queen of Great Britain and Ireland, residing at Hammersmith, London, in the county of Middlesex, England, have invented Improvements in or Applicable to Dredging Apparatus, of which the following is a specification.

This invention has been patented in the following countries: Great Britain, December 13, 1892, No. 22,913; Russia, December 31, 1894, (old style,) No. 24,567; France, October 25, 1893, No. 233,629; Belgium, November 29, 1893, No. 107,407; Spain, February 10, 1894, No. 15,347; Italy, December 31, 1893, No. 319, Vol. LXIX; Austria, May 19, 1894, No. 166; India, April 27, 1894, No. 15; Victoria, January 9, 1894, No. 11,074; New South Wales, December 29, 1893, No. 4,807, and New Zealand, February 13, 1894, No. 6,672.

This invention has reference to improvements in or applicable to dredging apparatus of the kind wherein material such as silt, mud, sand, or gravel is raised by means of water through a suction-pipe connected to a centrifugal pump or equivalent device and equipped with means for agitating the mud by jets of water; and my invention has for its object to avoid difficulties heretofore arising from variations in the nature of the earth to be raised and from fractures or derangement of the parts or a clogging of the pipe by large articles, as pieces of rope, drawn into the apparatus. I provide the lower end of the suction-pipe with detachable and exchangeable nozzles through which jets of any size desired of water under pressure are forced in such a manner as to disintegrate, break up, or loosen the said material and render it capable of being readily withdrawn through the suction-pipe with the water drawn therethrough. By making the nozzles exchangeable I can easily and rapidly repair damages if a nozzle is broken and can vary the action according to the character of the silt or other material to be dredged.

In the accompanying drawings, Figure 1 shows in vertical section, and Fig. 2 in plan,

the lower end of a suction-pipe constructed with nozzles according to this invention and 50 suitable for connection to a centrifugal pump or equivalent device. Figs. 3 and 4 show in elevation alternative forms of nozzles that may be used.

A is a pipe, preferably of wrought-iron or 55 steel, forming the lower portion of a pump suction-pipe. The lower end or mouth of this pipe A is conically enlarged and is provided with a grid or guard B to prevent too large pieces of the more or less disintegrated material being drawn into the suction-pipe.

C is a sheet-metal casing arranged to surround the lower enlarged end of the pipe A, to which it is firmly secured by angle-iron rings C' C² and rivets, so as to form, with the 65 said pipe, an annular water-tight chamber D. Screwed into the upper end of this casing C is a union E adapted to receive the lower end of a flexible pipe F, which is suitably connected to a force-pump (not shown) by which 70 water under considerable pressure can be forced into the chamber D.

G is a perforated metal ring firmly secured to the lower end of the chamber D and serving in the example shown to hold the grid B 75 in place. To the lower side of this ring and in line with the perforations G' therein and in the lower side of the chamber D are fixed a series of exchangeable nozzles H, which are consequently arranged in a circular row 80 around and below the mouth or lower end of the suction-pipe A and through which water under pressure can be caused to pass from the chamber D. In the drawings I have shown six nozzles; but it will be obvious that 85 I do not limit myself to this number, as the same may be varied according to circumstances. These nozzles are each fixed at a slight angle to the vertical in order that the water forced through them shall be directed 90 toward the axis of the suction-pipe A and thereby more effectually break up or loosen the material directly under the grid or guard B of the said suction-pipe. The grid or guard B is confined by means of the ring G, which 95 carries the nozzles. (See Fig. 1.) It can be

- removed for repair or exchange by simply removing the ring and nozzles, after which the same or another of a finer or coarser grade can be again secured by the same means.
- 5 Each of the nozzles may be cast with a flange H', as shown in Fig. 3 and in dotted lines at the left-hand side of Fig. 2, so that it can be fixed to the ring G by means of studs and nuts; or they may be each formed with a screw F² and a hexagonal or other suitably-shaped shoulder H³, as shown in Fig. 4 and at the right-hand side of Fig. 2. Each can thus be attached to the ring G and detached at will.
- 5 The grid B being at the bottom of the structure serves efficiently to prevent the entrance of any obstruction and also distributes the induction of the water loaded with the earthy matter, so that it inducts with practical uniformity over the whole area.

What I claim is—

In a dredging apparatus the combination with a suction pipe having a grid at its lower end, of a water tight chamber surrounding the same with a connecting pipe for receiving water under pressure and a series of detachable and exchangeable water nozzles secured below said chamber and in communication therewith, the grid being held by a ring G in which said nozzles are set so that detaching the ring will not only remove the nozzles but will also liberate the guard and allow it to be repaired or exchanged, all substantially as herein specified. 25 30

In testimony whereof I have signed my name to this specification in the presence of two subscribing witnesses.

JOHN GWYNNE.
